10 Claims. (Cl. 321—48)

1

My invention relates to a method and apparatus for controlling voltage and more particularly to a method and apparatus for producing, with low impedance, a variable unidirectional voltage of controllable sign or polarity and amplitude in a simple, expeditious and convenient manner.

My method and apparatus can transform electric power from alternating current to direct current or may transform direct current to alternating current in a simple and efficient manner.

In the prior art variable direct voltage current from an alternating current source is obtained largely by the use of such instrumentalities as the thyratron, the ignitron or the amplidyne. These devices are costly and cumbersome. The thyratron and ignitron are essentially unidirectional devices conducting current in one direction only. They are controlled by controlling their phase or starting time within the positive half of the A.-C. cycle. They do not extinguish until the positive voltage and current through them are reduced to zero. They cannot be used to open a circuit carrying current. Although they are in themselves low impedance devices, they normally conduct only a fraction of the time, hence the impedance they present to the load is that of the supply divided by the total time over the conduction time. Since they will conduct current in one direction only, they will not hold down an overriding voltage (i. e. dynamically brake or damp a motor they may be driving). The amplidyne is not only costly but is heavy and its response is sluggish so that there is a tendency to produce a lag.

One object of my invention is to provide a means and method of producing a variable unidirectional voltage of controllable polarity and amplitude which is relatively light in weight.

Another object of my invention is to produce a variable voltage source which is inexpensive in construction and efficient in operation.

Another object of my invention is to provide a low impedance, variable unidirectional voltage source which is fast in response and simple to construct.

A further object of my invention is to provide low impedance variable unidirectional voltage source of controllable polarity and amplitude using a vibrating contact relay, wherein current may flow in both directions, and is hence inherently effective in damping its load.

Other and further objects of my invention will appear from the following description.

In general my invention contemplates the controlled transformation of power in an efficient

2

and simple manner from alternating current to direct current and from direct current to alternating current by improved circuits employing a vibrating contact relay. My system is admirably adapted for use in applications as a converter, inverter and in control equipment such as battery chargers, generator field controls, motor controls, illumination controls, alternating current power controls, rectified direct current power sources for electronic equipment, in electroplating and in analogous applications.

In my system, I am enabled to create a source of direct current voltage of any desired value from maximum negative voltage through zero to 15 a maximum positive voltage by simply controlling the phase of the excitation of the relay coil. The values of the maximum direct current voltages will be equal to the alternating current voltage applied to the relay contacts as read on an averaging type meter. The resistance of the direct current source will be equal to the impedance of the alternating current supply added vectorially to the direct current resistance of the filter choke and the commutating resistors. The current 20 which will flow in the direct current resistance load will be equal to the voltage to which the source is set, divided by the source plus the load resistances.

If a direct current voltage such as a battery 25 or the back electromotive force of a motor exists in the load, the current will be equal to the source voltage less the load voltage, divided by the load plus the source resistances. If the load voltage should exceed the source voltage, the current will 30 reverse and power will be fed from the direct current load to the alternating current supply. This unusual characteristic is of great value when my method and apparatus are applied for the control of devices having direct current motors.

I am thus enabled dynamically to brake the direct current motors as well as to accelerate, decelerate, reverse and regulate them at any speed from zero 35 to full speed in either direction without concomitantly incurring the necessity of dissipating large amounts of heat in the motor or in control rheostats.

I am further enabled to employ polyphase alternating current power sources by employing multiple relays, using one for each phase and in 40 this manner I am enabled to handle large amounts of power to obtain direct current with extremely low amounts of ripple. Furthermore, I may parallel any number of relays on single or polyphase circuits in order to obtain any desired 45 amount of direct current power output.

In the accompanying drawings which form part of the instant specification and which are to be read in conjunction therewith, and in which like reference numerals are used to indicate like parts in the various views:

Figure 1 is a diagrammatic view of a circuit capable of carrying out the method and embodying the apparatus of my invention.

Figure 2 is a diagrammatic view of another circuit capable of carrying out the method and embodying the apparatus of my invention.

Figure 3 is a view of a circuit showing another form of apparatus capable of carrying out my method and embodying the apparatus of my invention and employing a saturable reactor in the circuit.

Figure 4 is a diagrammatic view showing my method and apparatus applied as an inverter to produce an alternating current output from a direct current input.

Figure 5 is a series of curves of voltage plotted against time illustrating the action of my method and apparatus.

Figure 6 is a diagrammatic view showing the construction of a relay suitable for use in carrying out my invention.

Referring now to Figure 1, the output of an alternating current source 1 of any suitable frequency and voltage is impressed across the primary winding 2 of a transformer 3. The ends of secondary winding 4 are connected by conductors 5 and 6 to contact points 7 and 8 of a vibrating contact relay 9 through commutating resistors 10 and 11. The relay 9 may be of any suitable type. A relay manufactured by the Western Electric Company under the identification D-168479 is especially suitable for use in my method and apparatus. The relay is polarized, as can be seen by reference to Figure 1. The controlled polarizing current is supplied to the coil 12 from a battery 13 through conductors 14 and 15 and 19, and variable resistor 16. Alternatively, the vibrating contact 17 may be given magnetic polarity by including it in a magnetic flux path in any suitable manner known to the art.

Referring now to Figure 6, a core 205, made of magnetic material, carries a winding 212 and a winding 219. The vibrating armature 217, which is adapted to make contact with stationary contact points 207 and 208, is flexibly mounted from the core 205 in any appropriate manner as, for example, by flexible connection 220. A D.-C. polarizing current may be passed through terminals 201 and 202 and the relay exciting current may be passed through terminals 203 and 204. If desired, the D.-C. polarizing current may be passed through terminals 203 and 204 while the signal currents may be passed through terminals 201 and 202.

It is to be understood that the showing of the relay is diagrammatic and illustrative only and that any suitable relay may be employed. It is preferable to use a relay armature which has no return spring such as shown in Figure 6, thus making the relay entirely aperiodic and enabling the relay to be operated at extreme speeds.

The fact that the relay has no period of its own enables me to control the phase of the contact operation in a manner which will not be influenced by the mechanical resonance of the relay.

One side of the coil 12 is connected to the mid-tap of the secondary winding 4 by conductors 15 and 20. A phase shifting network comprising a capacitor 21 and a variable resistor 22 is con-

nected in parallel with the secondary winding 4. The upper end of the coil 12 is connected to a point between capacitor 21 and resistor 22 by means of conductor 23 and variable capacitor 24. The capacitor 24 isolates the battery 13 from the alternating current power supply and prevents its being short-circuited. The value of the capacitor 24 may be varied to determine the initial phase setting.

One direct current output terminal 25 is connected to the midpoint of the secondary winding 4 by conductors 26, 15 and 20. The other direct current output terminal 27 is connected to the vibrating contact 17 through conductor 28 and choke coil 29 which filters and smooths the direct current output. A capacitor 30 and a capacitor 31 are connected in parallel with the contacts 7 and 8 to bypass transients and suppress sparking.

The operation of the apparatus shown in Figure 1 and my method can best be understood by reference to Figure 5 in conjunction with Figure 1. The curve A represents the alternating voltage occurring at the upper contact 7 which is connected to the upper end of the secondary winding 4. The curve B represents the voltage occurring at the lower contact 8 of the relay which is connected to the lower end of the secondary winding 4. In the curves it has been assumed that the relay has a negligible transfer time. Actually the relay has a very small transfer time. It is sufficiently small as to be negligible so that the curves represent what actually occurs for all practical purposes.

Referring to Figure 1, the potential of the point, connecting condenser 21 and resistor 22 with respect to the center tap of secondary winding 4, is a relatively constant A.-C. value which can be rotated in phase by the adjustment of resistor 22. Adjustment of condenser 24 will change the phase of the current passed through condenser 24 and coil 12 with respect to the voltage across them. Setting the value of condenser 24 can be used to make the relay phase correct for maximum and minimum settings of resistor 22.

Let us now assume that the upper end of secondary winding 4 is going positive. A transient voltage will be impressed from the upper end of winding 4 through the capacitor 21 through the capacitor 24 through the winding 12 through the conductors 15 and 20 to the mid-tap of the winding 4. A transient voltage will also be impressed from the mid-tap of winding 4 through conductors 20 and 15 through the winding 12 through conductor 14 through conductor 23 through capacitor 24 through resistor 22 to the other side of the winding 4. It will be observed that the direction of the voltage from the upper end of the winding 4 opposes the direction of the voltage from the mid-tap of winding 4 to the lower end thereof. The voltage impressed across the winding 4 is through capacitors so that the voltage will lead the current. The voltage in the opposite direction is impressed from the mid-tap of the winding 4 to the lower end of the winding through a variable resistor 22. This voltage will be more in phase with the current flowing through winding 12. In other words, the voltage drop through the capacitor 21 and the voltage drop through the resistor 22 will equal the voltage across the winding 4. The reduction of the IR drop across the resistor 22 will increase the voltage drop due to the capacitive impedance of the capacitor 21. Similarly an increase of the IR drop across the resistor 22 will decrease the capacitive impedance

drop across condenser 21. Since the effect of the capacitor is to make the voltage lead the current a variation of the value of the resistance of the resistor 22 will shift the phase of the current flowing through the coil 12.

For the operation shown by curve C of Figure 5 the adjustment of the resistor 22 is at its maximum value and condenser 24 is so set and the coil current is such that the vibrating contact 17 is in contact with upper contact 7 as soon as the upper portion of secondary winding 4 is of positive polarity. A positive potential is then applied from the upper end of secondary winding 4 through conductor 5 through resistor 10 through contact point 7 through vibrating contact 17 through conductor 28 to terminal 27 through the external circuit (not shown) to terminal 25 through conductors 26 and 15 and 20 to the mid-tap of secondary winding 4. As soon as the polarity of the upper end of winding 4 becomes negative, the vibrating contact 17 moves under the influence of the field generated by the current flowing through coil 12 (now in the opposite direction) to make contact with contact point 8. When the upper end of the secondary winding 4 is going negative the lower end of winding 4 is going positive so that the positive potential will be applied from the lower end of secondary winding 4 through conductor 6, resistor 11, contact point 8 to the center contact 17 again in a direction to make terminal 27 of positive polarity.

Let us now reduce the value of the resistance of the resistor 22 to vary the phase of the current through the relay control winding 12 so that the shift of the vibrating contact 17 from contact point 7 to contact point 8 occurs somewhat earlier than the shift of voltage across the secondary winding 4. What then occurs is shown in curve D of Figure 5. The upper end of coil 4 goes negative earlier in the cycle causing the current through winding 12 to cause the center contact 17 to make contact with contact point 8 until somewhat earlier in the cycle. The average potential of the positive pulses is greater than the average of the negative pulses and the over-all effect across the terminals 27 and 25 is a reduced voltage, the ripple of which has been smoothed by the choke coil 29. When the advance of the shifting is 90°, the effect obtained is that shown in curve E of Figure 5 in which the positive pulses are of the same amplitude and duration as the negative pulses so that the average voltage across the output contacts 27 and 25 will be zero.

When the advance of the shifting is more than 90° but less than 180°, the polarity across output terminals 27 and 25 is reversed though the amplitude is still not at maximum. This is shown by curve F of Figure 5 in which the negative pulses are of greater duration and amplitude than the positive pulses so the over-all effect is a negative polarity at terminal 27 though of reduced amplitude. When the value of the resistor is at a minimum the capacitive impedance drop across capacitor 21 is at a maximum. A full amplitude direct current voltage of opposite polarity is obtained since the phasing current in coil 12 will be 180° out of phase with the voltage across secondary winding 4. In this case whenever the upper end of secondary winding 4 is of positive polarity the current flow through coil 12 is such that vibrating contact arm 17 is in contact with contact point 8. As soon as the upper end of winding 4 goes negative the contact arm 17 shifts to make contact with stationary contact point

7. The action is shown by curve G of Figure 5 in which all of the pulses are in the negative direction giving maximum negative potential upon terminal 21.

5 It will be observed by those skilled in the art by simply controlling the phase of the excitation to the winding 12, I am enabled to create a source of direct current voltage of any desired value from maximum negative voltage through zero to maximum positive voltage. The resistance of the direct current source will be equal to the impedance of the alternating current supply added vectorially to the direct current resistance of the filter choke in the supply. The housing 13 in which the relay is positioned may be constructed to suppress sparking as for example by placing the interior under a vacuum or by filling the casing 18 with inert gas under pressure. With a 60 cycle single phase alternating current supply 20 the ripple is 120 cycles per second which is sufficiently smoothed by the filter coil 29.

My new method and apparatus enable me to control and regulate with precision all direct current equipment such as direct current motors. 25 My system has the advantage over thyratron and ignition controls in that the relay contacts can conduct current in either direction whereas the thermionic discharge devices can conduct current in one direction only. This characteristic enables me to control an over-run load and to obtain quick dynamic braking. Furthermore, by means of my system I may control servomechanisms for many applications as well as machine tools, sewing machines and the like.

30 In a battery charger the ease of control of the charging rate is peculiarly advantageous and the low resistance in the direct current output gives a desirable tapered charging rate.

My improved controlled direct current supply 40 is eminently adapted for the regulation of voltages and currents in electric plating. Furthermore the simplicity and ease of control permits the use of separate units for individual plating tanks thus increasing the ease of handling 45 different types of work.

I am enabled by my system to provide direct current power at voltages which may be varied over a wide range and regulated to a high degree of accuracy against line voltages and load changes 50 thus adapting my improved supply for electronic applications such as radar, television, induction heating, and the like.

It is to be understood that Figure 1 is a presentation of my method and apparatus in a simple 55 form, employing a simple phase shifting network. Any suitable phase shifting network known to the art may be employed as will be readily understood by those skilled in the art.

Referring now to Figure 2, I have shown a modified circuit embodying the apparatus of and capable of carrying out the method of my invention, in which I may employ lighter phasing equipment. In Figure 2, a network comprising a variable capacitor 50 and a variable resistor 60 51 are connected in series in parallel relation with the secondary winding 4. A second network comprising a variable resistor 32 and a variable capacitor 33 are connected across the secondary winding 4. The value of the capacity of the capacitor 50 and the value of the resistance of the resistor 51 governs the phase of the potential at point 34. The value of the resistance of resistor 32 and the value of the capacity of capacitor 33 governs the phase of the voltage at point 70 75 35. Connected across points 34 and 35 is a phase

shifting network comprising a capacitor 36 analogous to capacitor 21 in Figure 1 and a resistor 37 analogous to the resistor 22 in Figure 1. The network comprising resistor 32 and capacitor 33 is a phase limiting control for point 35. The network comprising capacitor 50 and resistor 51 is a phase limiting control for point 34. The variable resistor 37 is a phase shifting control for governing the amplitude and polarity of the output voltage. The anode 38 of a thermionic tube 39 is connected to the positive terminal of the battery 13 through control coil 12 and the conductors 14 and 40. A screen grid 41 is connected to a voltage divider 42 by variable arm 43. The screen grid acts as a polarization control. The control grid 44 of the thermionic tube is connected to a point between capacitor 36 and variable resistor 37 by conductor 23 and capacitor 24. The cathode 45 of the tube 39 is connected to the mid-point of secondary winding 4 through conductor 46.

The operation of the circuit as shown in Figure 2 is essentially the same as that shown in Figure 1. I am enabled, however, to use much lighter phasing equipment. The value of the current flowing through control coil 12 of the relay 9 is governed by the potential applied to the control grid 44. This is represented by the IR drop across resistor 52. When the resistance of control resistor 37 is at a maximum, the phasing current in control coil 12 will be such that the contacts will be in phase with the voltage across secondary winding 4 and the voltage across output terminals 27 and 25 will be at a maximum amplitude. When the resistance across control resistor 37 is at a minimum, the current flowing through coil 12 will be approximately 180° out of phase with the voltage across secondary winding 4 and the voltage across output terminals 27 and 25 will again be at a maximum amplitude but of opposite polarity. By means of my phase limit control circuits, I am enabled to obtain a shift of more than 180° by adjustments of capacitors 50 and 33 and adjustments of resistors 32 and 51.

Referring now to Figure 3, there is shown another form of apparatus embodying and capable of carrying out the method of my invention in which a saturable reactor is used to govern the phase of the control current through coil 12 of the relay. A saturable reactor indicated generally by the reference numeral 60 has a winding 61 connected in series with a resistor 62 across the transformer secondary 4. The control coil 12 of the relay is connected across the resistor 62 and the IR drop across this resistor will govern the current flowing through the coil 12. A capacitor 63 is placed in the circuit to govern the initial phase set. The control winding 64 of the saturable reactor is connected in series with a thermionic tube 65; the winding 64 and the tube 65 being connected across the secondary winding 4 by means of conductors 66 and 67. The phase of the current flowing through the control coil 12 is governed by the phase of the current flowing through the resistor 62. This in turn is governed by the current flowing through the circuit including the resistor 62 and the winding 61. The IX drop through winding 61 and the IR drop through resistor 62 will equal the voltage across the secondary winding 4. The phase of the current flowing through the inductance-resistance phase shifting circuit will depend on the relative values of the inductance and the resistance. A variation of the value of the inductance of the winding 61 will shift the phase

of the current flowing through the resistor 62 and hence through the control winding 12 of the relay 9. When the current flowing through winding 64 is of high value, the core becomes saturated and inductance of the winding 61 is at a minimum. When this condition prevails the control current 12 will be in phase with the voltage developed across the secondary winding 4 and the circuit is such that when the upper portion of secondary winding 4 is going positive the armature 17 of the relay will make contact with stationary contact point 7 so that the direct current output terminal 27 will be of positive polarity. Furthermore, when the control current 12 of the relay is exactly in phase with the voltage developed across the transformer secondary 4, the output voltage will be of maximum amplitude.

I provide a current path comprising capacitor 74 and the thermionic tube 65 across the upper branch of secondary winding 4. When conductor 5 is of positive polarity current will flow from conductor 5, through capacitor 74, through the plate to cathode circuit of the tube 65, through conductor 66 to the mid-tap of the secondary winding 4, thus charging the condenser 74. It will be observed that the lower plate of the capacitor 74 is always negative with respect to the upper plate and hence with respect to conductor 5. The control winding 64 of the saturable reactor is connected across the capacitor 74 so that the integrated charge of the condenser 74 will represent the integrated current flowing through the control winding 64. A permanent magnet shown diagrammatically and indicated by the reference numeral 12' is provided for polarizing the relay.

The condition of maximum current through the control winding 64 of the saturable reactor is brought about by impressing a high positive potential at control terminal 70 with respect to control terminal 71 during the time that the plate 76 of tube 65 is positive. This permits maximum current to flow from plate to cathode impressing a maximum charge on condenser 74. I use a capacitor of large capacity such as an electrolytic condenser, whereby during the half cycle when the upper point of secondary winding 4 is of negative polarity, the charge of the condenser will be sufficient to permit current to flow through the control winding 64 during this half cycle. On the next half cycle the condenser becomes charged again and current continues to flow through the winding 64 of the saturable reactor 60, at a value governed by the potential applied to the control grid 73.

Any suitable means for controlling the voltage across control terminals 70 and 71 may be employed. When this voltage is such that the grid is highly negative with respect to cathode, during the time conductor 5 is positive, the resistance of the thermionic tube will be increased to such point that it will become a non-conductor. When this point is reached, no charging current will flow through the capacitor 74 and hence no current will flow through the winding 64 of the saturable reactor and maximum inductance of winding 61 will be effective. When this condition prevails, maximum IX drop will appear across the reactor, the current will be a minimum, and the voltage across the output terminals 27 and 25 will be again of maximum amplitude but 180° out of phase with the voltage across the secondary winding 4. In other words, when the upper portion of secondary winding 4 is at its maximum positive value, the voltage at termi-

nal 27 will be of maximum negative polarity. Complete control of the entire range is easily exercised by controlling the voltage across control terminals 70 and 71. The principle involved is the same as that heretofore described and illustrated in Figure 5. A different phase control network is used to accomplish the same results and the circuit shown in Figure 3 is another embodiment of my invention.

Referring now to Figure 4, I have shown a circuit which is an inverter. One of the advantages of my method and apparatus is that current may be conducted in both directions. This was pointed out above in describing the application of my method and apparatus to the dynamic braking of direct current motors and their acceleration, deceleration and reversal.

This characteristic may be employed to provide an alternating current power supply from a direct current source, such as a battery, for the operation of alternating current equipment of all types and descriptions.

A source of direct current potential is applied across terminals 80 and 81. A pair of polarized relays 82 and 83 are employed, of the type similar to that described hereinabove. One terminal 80 of the direct current source is connected to a conductor 84 through choke and filter coil 85. One contact 86 of relay 82 is connected to the conductor 84 by the conductor 87. Contact point 88 of the relay 83 is connected to the conductor 84 by the conductor 89. The other terminal of the direct current input potential 81 is connected to a conductor 90. The other stationary contact 91 of the relay 82 is connected by conductor 92 to the conductor 90. The other stationary contact 93 of the relay 83 is connected by conductor 94 to the conductor 90. The control winding 95 of the relay 82 and the control winding 96 of the relay 83 are connected in series by a conductor 97. The other end of control winding 95 is connected by conductors 106 and 107 to the moving contact 98 of the relay 82. The other end of the winding 96 is connected by conductor 99, resistor 100 and conductor 101 to the moving contact 102 of the relay 83. Conductors 99 and 106 are inter-connected by a capacitor 103, the value of which sets the output frequency. The resistor 100, if desired, may be a choke coil in order to obtain better frequency stability. Polarizing coils 95' and 96' connected across the D-C. input are provided. The current flowing through the polarizing coils is governed by the variable resistor 16.

In operation, let us assume the armatures 98 and 102 of the relays 82 and 83 are in the position shown in Figure 4. Current will flow from terminal 80 through the choke coil 85, through the conductor 87, through the conductor 107, through the control winding 95 of the relay 82, through conductor 97, through the control winding 96 of the relay 83, through the conductor 99, through the resistor 100, through conductor 101, through armature 102, through conductor 94, through conductor 90 and thence to the other terminal 81 of the direct current source. The energization of the control windings 95 and 96 causes the armatures 98 and 102 of the polarized relays 82 and 83 to shift so that contact will be made by armature 98 with contact point 91 and by armature 102 with contact point 88.

During the flow of current just described, that is, with armature 98 in contact with contact point 86 and armature 102 in contact with contact point 93, alternating current output terminal 108 was the same polarity as direct cur-

rent potential terminal 80. Similarly, alternating current output terminal 109 was of the same potential as direct current potential terminal 81. The capacitor 103 will have become charged to continue the flow of current momentarily for a time, depending upon the capacity of the condenser.

When the shift of relay armatures takes place current will flow from terminal 80 through the choke coil 85, through conductor 89 to contact point 88 to armature 102. It will be observed that alternating current output terminal 109 is now connected with opposite polarity. The circuit is completed through conductor 101, through resistor 100, through conductor 99, through control winding 96 of relay 83, through conductor 97, through control winding 95 of relay 82, through conductor 106, conductor 107, through armature 98, through contact point 91, conductor 92 to the other direct current terminal 81.

The shifting of the relay armatures does not instantaneously shift the voltage across alternating current terminals 108 and 109 due to the effect of the capacity of the network. The frequency of the output alternating current will depend upon the value of the capacitor 103 and it may be adjusted to obtain any desired frequency.

It is to be understood that the above circuits are given by way of illustration and not by way of limitation and that my method and apparatus are susceptible of many applications within the spirit of my invention. As will be readily understood by those skilled in the art, three relays in parallel may be employed to convert three-phase input power to a direct current output. In such case, the ripple is greatly reduced. In the circuit three power transformers may be employed in which one primary is connected across the first and second line. One primary is connected across the first and third line and one primary is connected across the first two primary windings. The secondaries of each of the transformers are connected to the stationary contacts of the relay as shown in Figure 1.

My method and apparatus similarly may be used for power interchange between two non-synchronous alternating current systems.

It will be seen that I have accomplished the objects of my invention. I provide a method and apparatus for inter-transforming electric power from alternating current to direct current or vice versa in a simple and efficient manner. I have avoided the use of costly and cumbersome devices such as the thyratron, the ignitron or the amplidyne. I have provided a means and method of producing a variable unidirectional voltage of controllable polarity and amplitude which is light in weight, inexpensive in construction and efficient in operation. I have made available to the art a low impedance variable unidirectional voltage source which is fast in response and simple to construct. I have provided an apparatus employing a vibrating contact relay in which current may flow in both directions and which is hence inherently effective in damping the output load.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is therefore understood that my invention is not to

be limited to the specific details shown and described.

Having thus described my invention, I claim:

1. Apparatus for inter-converting alternating current to an output current having a direct current component including in combination a relay having a pair of stationary contacts and a vibrating contact adapted to make alternate connection with the stationary contacts, means for supplying alternating potential to the stationary contacts, means including the vibrating contact for removing direct current, a choke coil connected in series on the output side of the vibrating contact, means for vibrating the vibrating contact at the frequency of the alternating potential, phase-shifting means for shifting the phase between the vibration of the vibrating contact and the alternating potential through an angle greater than ninety electrical degrees to control the direct current component both in amplitude and polarity comprising a network having a capacitor and a resistor in series and means for varying the relative value of the resistance of the resistor with respect to the capacity of the capacitor.

2. Apparatus for inter-converting alternating current to an output current having a direct current component including in combination a relay having a pair of stationary contacts and a vibrating contact adapted to make alternate connection with the stationary contacts, means for supplying alternating potential to the stationary contacts, means including the vibrating contact for removing direct current, a choke coil connected in series on the output side of the vibrating contact, means for vibrating the vibrating contact at the frequency of the alternating potential, phase-shifting means for shifting the phase between the vibration of the vibrating contact and the alternating potential through an angle greater than ninety electrical degrees to control the direct current component both in amplitude and polarity comprising a network having a first resistor and capacitor in series, a second resistor and capacitor in series and a third resistor and capacitor in series, the third resistor and capacitor being connected across a point between the first resistor and capacitor and a point between the second resistor and capacitor.

3. Apparatus for inter-converting alternating current to an output current having a direct current component including in combination a relay having a pair of stationary contacts and a vibrating contact adapted to make alternate connection with the stationary contacts, means for supplying alternating potential to the stationary contacts, means including the vibrating contact for removing direct current, a choke coil connected in series on the output side of the vibrating contact, means for vibrating the vibrating contact at the frequency of the alternating potential, phase-shifting means for shifting the phase between the vibration of the vibrating contact and the alternating potential through an angle greater than ninety electrical degrees to control the direct current component both in amplitude and polarity comprising a network having a first resistor and capacitor in series, a second resistor and capacitor in series and a third resistor and capacitor in series, the third resistor and capacitor being connected across a point between the first resistor and capacitor and a point between the second resistor and capacitor and means for varying the relative value of the third resistor with respect to the third capacitor.

4. Apparatus for inter-converting alternating current to an output current having a direct current component including in combination a relay having a pair of stationary contacts and a vibrating contact adapted to make alternate connection with the stationary contacts, means for supplying alternating potential to the stationary contacts, means including the vibrating contact for removing direct current, a choke coil connected in series on the output side of the vibrating contact, means for vibrating the vibrating contact at the frequency of the alternating potential, phase-shifting means for shifting the phase between the vibration of the vibrating contact and the alternating potential through an angle greater than ninety electrical degrees to control the direct current component both in amplitude and polarity comprising a network having an inductor and a resistor and means for changing the relative value of the inductance of the inductor with respect to the resistance of the resistor.

5. Apparatus for inter-converting alternating current to an output current having a direct current component including in combination a relay having a pair of stationary contacts and a vibrating contact adapted to make alternate connection with the stationary contacts, means for supplying alternating potential to the stationary contacts, means including the vibrating contact for removing direct current, a choke coil connected in series on the output side of the vibrating contact, means for vibrating the vibrating contact at the frequency of the alternating potential, phase-shifting means for shifting the phase between the vibration of the vibrating contact and the alternating potential through an angle greater than ninety electrical degrees to control the direct current component both in amplitude and polarity comprising a network having an inductor and a resistor and magnetically saturable means for changing the inductance of the inductor.

6. Apparatus for inter-converting alternating current to an output current having a direct current component including in combination a transformer having a secondary winding, a relay having a pair of stationary contacts and a vibrating contact, means providing a conducting path between one end of the secondary winding and one of the stationary contacts, means for providing a conducting path between the other end of the secondary winding and the other of the stationary contacts, a pair of output current terminals, means providing a conducting path between one of the output current terminals and an intermediate point of the secondary winding, means including a choke coil providing a conducting path between the other of the output current terminals and the vibrating contact, means for vibrating the vibrating contact at the frequency of the alternating potential of the secondary winding, means for shifting the phase of the vibration of the vibrating contact with respect to the alternating potential through an angle greater than ninety electrical degrees to control the direct current component both in amplitude and polarity comprising a capacitor and resistor connected in series across the secondary winding.

7. Apparatus for inter-converting alternating current to an output current having a direct current component including in combination a transformer having a secondary winding, a relay having a pair of stationary contacts and a

vibrating contact, means providing a conducting path between one end of the secondary winding and one of the stationary contacts, means for providing a conducting path between the other end of the secondary winding and the other of the stationary contacts, a pair of output current terminals, means providing a conducting path between one of the output current terminals and an intermediate point of the secondary winding, means including a choke coil providing a conducting path between the other of the output current terminals and the vibrating contact, means for vibrating the vibrating contact at the frequency of the alternating potential of the secondary winding, means for shifting the phase of the vibration of the vibrating contact with respect to the alternating potential through an angle greater than ninety electrical degrees to control the direct current component both in amplitude and polarity comprising a capacitor and resistor connected in series across the secondary winding and means for varying the relative value of the resistance of the resistor with respect to the capacity of the capacitor.

8. Apparatus for inter-converting alternating current to an output current having a direct current component including in combination a transformer having a secondary winding, a relay having a pair of stationary contacts and a vibrating contact, means providing a conducting path between one end of the secondary winding and one of the stationary contacts, means for providing a conducting path between the other end of the secondary winding and the other of the stationary contacts, a pair of output current terminals, means providing a conducting path between one of the output current terminals and an intermediate point of the secondary winding, means including a choke coil providing a conducting path between the other of the output current terminals and the vibrating contact, means for vibrating the vibrating contact at the frequency of the alternating potential of the secondary winding, means for shifting the phase of the vibration of the vibrating contact with respect to the alternating potential through an angle greater than ninety electrical degrees to control the direct current component both in amplitude and polarity comprising an inductor and resistor connected in series across the secondary winding.

9. Apparatus for inter-converting alternating current to an output current having a direct current component including in combination a transformer having a secondary winding, a relay having a pair of stationary contacts and a vibrating contact, means providing a conducting path between one end of the secondary winding and one of the stationary contacts, means for providing a conducting path between the other end of the secondary winding and the other of the stationary contacts, a pair of output current terminals, means providing a conducting path between one of the output current terminals and an intermediate point of the secondary winding, means including a choke coil providing a conducting path between the other of the output current terminals and the vibrating contact, means for vibrating the vibrating contact at the frequency of the alternating potential of the sec-

ondary winding, means for shifting the phase of the vibration of the vibrating contact with respect to the alternating potential through an angle greater than ninety electrical degrees to control the direct current component both in amplitude and polarity comprising a resistor and an inductor connected in series across the secondary winding and means for varying the relative value of the inductance of the inductor with respect to the resistance of the resistor.

10. Apparatus for inter-converting alternating current to an output current having a direct current component including in combination a transformer having a secondary winding, a relay having a pair of stationary contacts and a vibrating contact, means providing a conducting path between one end of the secondary winding and one of the stationary contacts, means for providing a conducting path between the other end of the secondary winding and the other of the stationary contacts, a pair of output current terminals, means providing a conducting path between one of the output current terminals and an intermediate point of the secondary winding, means including a choke coil providing a conducting path between the other of the output current terminals and the vibrating contact, means for vibrating the vibrating contact at the frequency of the alternating potential of the secondary winding, means for shifting the phase of the vibration of the vibrating contact with respect to the alternating potential through an angle greater than ninety electrical degrees to control the direct current component both in amplitude and polarity comprising a resistor and an inductor connected in series across the secondary winding, means including a saturable reactor for varying the inductance of the inductor and means for controlling the saturation of the reactor.

FRANCIS H. SHEPARD, JR.
